UNITED STATES PATENT OFFICE.

HARRY R. CANFIELD, OF CLEVELAND, OHIO, ASSIGNOR TO THE ELECTRIC CONTROLLER & MANUFACTURING COMPANY, OF CLEVELAND, OHIO, A CORPORATION OF OHIO.

OVERLOAD DEVICE.

1,293,697.

Specification of Letters Patent. Patented Feb. 11, 1919.

Application filed April 19, 1916. Serial No. 32,221.

To all whom it may concern:

Be it known that I, HARRY R. CANFIELD, a citizen of the United States, residing at Cleveland, in the county of Cuyahoga and State of Ohio, have invented new and useful Improvements in Overload Devices, of which the following is a specification.

This invention relates to electromagnetic overload devices, and particularly to those having time-interval features.

The principal object of this invention is to provide an overload device, the operation of which is delayed for an interval of time after the occurrence of the overload, if the overload is less than the predetermined amount, and which, on excessively high or dangerous overloads, operates instantaneously. Another object is to provide an overload device in which the time-interval elements are hermetically sealed in a container to exclude dust, dirt, moisture, etc. Other objects will be apparent from the following specification.

In the accompanying drawing, Figure 1 is a cross-sectional view of one form of my invention; Fig. 2, a cross-sectional view showing a modification thereof; and Fig. 3, a partial cross-sectional view of another modification.

Referring to Fig. 1, 11 is a winding energized by current in a controlled circuit, not shown. 10 is a main magnetic frame containing the winding 11 and having a removable pole-piece 12 to facilitate assembling and inspection. 13 is a magnetic plunger which is attracted toward the pole-piece 12 by magnetic flux across the gap 14 when the winding 11 is energized. The lower threaded end of the plunger is screwed into the upper end of the hollow cylinder 15 of preferably non-magnetic material. The upper end of the plunger 13 may be hexagonal or square to receive a wrench. By means of the flange 16 on the plunger and the packing washer 17 between the flange and the cylinder 15, the cylinder is hermetically sealed when the plunger is screwed into it. The lower end of the cylinder 15 rests on an adjustable pedestal 19 threaded into a bracket 20 attached to the magnetic frame 10, so that, by adjusting the pedestal, the length of the air-gap 14 may be varied. Within the cylinder 15 is the magnetic piston 21, immersed or partly immersed in a heavy liquid 22, such as

mercury or a heavy basic solution. The piston 21 is preferably cylindrical with a small clearance between its circumference and the wall of the cylinder 15, and has the interior cavity 23, in general cone-shaped, terminating at the upper end in the small orifice 36. Between the piston 21 and the plunger 13 is another magnetic air-gap 30. The plunger 13 carries the upwardly projecting stem 24 for engaging the switch-arm 25 to open the contacts 26 and 27, which may thereby interrupt the circuit including the wires 28 and 29 for controlling a circuit-breaker, not shown.

The operation of the device shown on Fig. 1 is as follows: When an overload of small or ordinary value occurs in the winding 11, flux is generated thereby in the main frame 10, the piston 21, the gap 30, the plunger 13, the gap 14, and the pole-piece 12. This flux in the gap 14 exerts an upward pull on the plunger 13, and the flux in the gap 30 exerts an upward pull on the piston 21. The flux in the gap 14 is insufficient to lift the plunger 13 and the attached cylinder 15 and its contents, but the flux in the gap 30 is sufficient to lift the piston 21 which moves slowly and uniformly under the restraining action of the liquid 22. The initial upward movement of the piston 21 causes it to emerge from the liquid and to lift the portion of the liquid in the interior cavity 23. The weight of this portion of the liquid balances the magnetic pull in the gap 30, causing the upward movement of the piston 21 to cease. The air above the piston 21 then passes through the orifice 36, allowing the level of the liquid in the cavity 23 to be slowly lowered. The weight of the liquid supported by the piston 21 becoming less, the piston again moves upward. This action continues, resulting in a slow upward movement of the piston 21, the rate depending upon the amount of magnetic pull in the gap 30 and the size of the orifice 36. The movement of the piston 21 is further steadied by the restricted flow of liquid and air downward between the piston and the wall of the cylinder. As the piston moves upward the magnetic reluctance of the gap 30 is gradually reduced, and more and more flux flows through the entire magnetic circuit. The pull on the piston 21 in the gap 30, therefore, increases and tends to accelerate the movement of the piston 21, but

this tendency is counteracted by so shaping the interior cavity 23 that as the piston moves upward the weight of the liquid lifted in a given unit distance will increase with the upward movement of the piston proportionately to the increase of magnetic pull, resulting in a uniform movement of the piston. However, I do not limit my invention to any definite shape of this cavity.

- 10 When the piston 21 has approximately reached the plunger 13, the reluctance of the entire circuit has been decreased sufficiently to give sufficient flux in the gap 14 to lift the plunger 13, carrying with it the cylinder 15 and its contents, whereupon the stem 24 engages the arm 25, opening the controlling circuit of the circuit breaker, as described.
- 15

If the overload in the winding 11 is somewhat greater than that assumed in the case just described, the flux in the entire circuit will be greater and the piston 21 will travel upwardly with greater rapidity, and before it has reached the plunger 13, the flux in the gap 14 will lift the plunger 13 and open the switch 25, and consequently the circuit breaker. If, however, the overload in the winding 11 is excessively high or dangerously large, the flux in the gap 14 will be sufficient to lift the plunger 13 together with the cylinder 15, the piston 21, and the liquid 22 at once without awaiting the independent movement of the piston 21. The greater the current in the winding 11, the faster will the piston move at any given point of its movement, due to its lifting a greater weight of liquid and to the greater rapidity with which the air will flow through the orifice 36, and hence the shorter will be the time-interval between the overload and operation.

By adjusting the pedestal 19 the length of the gap 14 may be adjusted to change the values of current in the coil 11 at which the device will operate. It will be understood, of course, that the relative positions of the plunger 13 and the piston 21 may be varied, as desired, by varying the length of the cylinder 15.

50 In the device shown in Fig. 2, an adjustable pole-piece 31 is provided to introduce another gap 32 between the pole-piece 31 and the lower end of the piston 21^a. The pedestal 19^a is in this case threaded in the pole-piece 31.

In the operation of the device shown in Fig. 2, the current in the winding 11 generates flux in the magnetic frame 10, the adjustable pole-piece 31, the air-gap 32, the piston 21^a, the air-gap 30, the plunger 13, the air-gap 14, and the pole-piece 12. The function of the gap 14 is the same as that described in connection with Fig. 1. The flux in the gaps 30 and 32 pull in opposite directions on the piston 21^a, the flux in the

gap 30 predominating, so that the piston 21^a moves upwardly. As the upward movement of the piston 21^a decreases the reluctance in the gap 30, it increases the reluctance in the gap 32, so that the flux in the entire circuit does not increase as rapidly as in the case of Fig. 1, and the movement of the piston 21^a is not so rapidly accelerated. The compensating effect of the hollow cavity in the piston 21^a, shown in Fig. 1, may be omitted, if desired, and the piston made solid. To steady the movement of the piston, any suitable liquid 22 may be used and a small clearance allowed between the piston and the wall of the cylinder.

55 In Fig. 3 are shown the movable parts only of another form in which no liquid is used. The piston 21^b is provided with the suction washer 33 and the adjustable air-port 34. A downwardly-projecting guide 35, preferably non-magnetic, is provided on the plunger 13 to centrally guide the piston 21^b. When the flux in the gap 30 lifts the piston 21^a, the air above the piston moves through the port 34 and the space below the piston and retards the upward movement of the piston, the operation of the rest of the device being the same as of that shown in Fig. 1.

60 It is apparent from the foregoing that other means than that shown for retarding the upward movement of the magnetic piston 21 in the cylinder 15 may be employed within the scope of my invention; that other adjustment features may be employed; that the shape of the interior cavity 23 of the piston 21 may be modified to control the rate of movement of the piston 21 as desired; and that other changes may be made without departing from the spirit of my invention. 10

I claim—

1. In an electromagnetic device, a winding, a casing and a magnetic member therein both influenced by current in the winding to move when the current is above a predetermined value, and means including means within the casing whereby the said movement of the casing is delayed by a time interval inversely proportional to the rate of movement of the magnetic member.

2. In an electromagnetic device, a winding, a casing and a magnetic member therein both influenced by current in the winding to move when the current is above a predetermined value, and means including a fluid in the casing whereby the said movement of the casing is delayed by a time interval inversely proportional to the rate of movement of the magnetic member.

3. In an electromagnetic device, a winding, a casing and a magnetic member therein both influenced by current in the winding to move when the current is above a predetermined value, and means including means within the casing whereby the said move- 1

ment of the casing is delayed by a time interval which is inversely proportional to the rate of movement of the magnetic member and which is decreased by an increase of 5 current in the winding.

4. In an electromagnetic device, a winding, a casing and a magnetic member therein both influenced by current in the winding to move when the current is above a predetermined value, and means including a fluid 10 in the casing whereby the said movement of the casing is delayed by a time interval which is inversely proportional to the rate of movement of the magnetic member and 15 which is decreased by an increase of current in the winding.

5. In an electromagnetic device, a winding, a casing and a magnetic member therein both influenced by current in the winding 20 to move when the current is above a predetermined value, means in the casing whereby the said movement of the magnetic member is retarded, and the movement of the casing is delayed until after the movement 25 of the magnetic member except when the current is above a second higher predetermined value.

6. In an electromagnetic device, a winding, a casing and a magnetic member therein 30 both influenced by current in the winding to move when the current is above a predetermined value, and means including a fluid in the casing whereby the said movement of the magnetic member is retarded, 35 and the movement of the casing is delayed until after the movement of the magnetic member except when the current is above a second higher predetermined value.

7. In an electromagnetic device, a magnetic circuit, a winding therefor, a movable member in the circuit influenced by current in the winding to move when the current is above a predetermined value, and means for delaying the said movement of the member 45 for a time interval, the said means comprising a movable element in said magnetic circuit having a dashpot connection with the said movable member.

8. In an electromagnetic switch, a magnetic circuit, a winding therefor, a movable member in the circuit influenced by current in the winding to move when the current is above a predetermined value, means for delaying the said movement of the member 50 for a time interval, the said means comprising a movable element in the magnetic circuit hermetically sealed within the movable member and movable relatively thereto, and means for retarding the relative movement.

9. In an electromagnetic switch, a magnetic circuit, a winding therefor, a movable member in the circuit influenced by current in the winding to move when the current 55 is above a predetermined value, means for

delaying the said movement of the member for a time interval except when the current is above a second predetermined value, the said means comprising a movable element in the magnetic circuit hermetically sealed 70 within the movable member and movable relatively thereto, and means for retarding the relative movement.

10. In an electromagnetic device, a magnetic circuit, a winding therefor, a movable member and a movable element in the circuit both influenced by current in the winding to move when the current is above a predetermined value, the movable member constituting a container for the movable element, and means whereby the said movement of the movable member is delayed until the reluctance of the circuit has been reduced by the movement of the element except when the current is above a second 85 predetermined value.

11. In an electromagnetic device, a winding therefor, two movable members forming the two elements of a dashpot and both influenced by current in the winding to move when the current is above a predetermined value, and means including a magnetic circuit of variable reluctance, whereby the said movement of one member is delayed until after the said movement of the other except 95 when the current is above a second predetermined value.

12. In an electromagnetic device, a magnetic circuit, a winding therefor, and two movable members in the circuit both influenced by current in the winding to move when the current is above a predetermined value, the two members forming the two elements of a dashpot, and means whereby the said movement of one member is delayed 100 until the reluctance of the circuit has been reduced by the said movement of the other members, except when the current is above a second predetermined value.

13. In an electromagnetic device, a winding therefor, a movable member influenced by current in the winding to move when the current is above a predetermined value, the movable member having a chamber movable therewith and a movable magnetic element 110 in the chamber, having a dashpot connection with the chamber, and means including a magnetic circuit, the reluctance of which varies on the movement of the movable element, whereby the movement of the member 115 is delayed until after the movement of the element, except when the current is above a second predetermined value.

14. In an electromagnetic device, a magnetic circuit, a winding therefor, a movable member in the circuit influenced by current in the winding to move when the current is above a predetermined value, the member having a hermetically sealed chamber movable therewith, a magnetic element of the 125 130

2

magnetic circuit in the chamber, and means whereby the said movement of the member is delayed until after the movement of the element except when the current is above a 5 second predetermined value.

15. In an electromagnetic device, a winding, a movable chamber-member influenced by current in the winding to move when the current is above a predetermined value only, 10 and means for delaying the movement of the chamber-member for a time interval, the said means comprising a movable element hermetically sealed within the chamber-member.

15. 16. In an electromagnetic device, a magnetic circuit, an energizing winding; a member adapted to be moved upwardly by the magnetic influence of the winding, and means for retarding the movement of the 20 member, comprising a body of liquid in which the member is positioned, the said member having therein a cavity commun-

cating below with the liquid and tapering upwardly to a restricted orifice.

17. In an electromagnetic device, a magnetic circuit, an energizing winding, a working gap in the circuit, a member adapted to be moved upwardly by the force of magnetic flux in the gap, the force increasing with the movement of the member, means for retarding the movement of the member, comprising a body of liquid in which the member is positioned, the said member having therein an upwardly tapering cavity communicating below with the liquid and having a restricted orifice above, the shape of the cavity and the size of the orifice being such that the weight of the member and the occluded liquid balances the variable magnetic pull during the upward movement of the member.

Signed at Cleveland, Ohio, this 14th day of April, A. D. 1916.

HARRY R. CANFIELD.
